(57) **CLAIM**

The ornamental design for a rigid shoe insert having a raised heel, as shown and described.

DESCRIPTION

FIG. 1 is a top perspective-view of a rigid shoe insert with raised heel, showing my new design;

FIG. 2 is a top view thereof;

FIG. 3 is a side view thereof;

FIG. 4 is a front elevation view thereof; and,

FIG. 5 is a rear elevation view thereof.

The broken line portions of FIGS. 1 and 3 are included to show unclaimed subject matter only and form no part of the claimed design.
